SYNCHRONOUS DETECTION CIRCUITS

Mathias Tong Yuan Tong, Paris, France, assignor to Compagnie d'Applications Mecaniques à l'Electronique, au Cinema et à l'Atomistique (CAMECA)

Filed Apr. 14, 1964, Ser. No. 359,610

Claims priority, application France, Apr. 17, 1963, 359,610

2 Claims. (Cl. 328—133)

The present invention relates to synchronous detector circuits of the two triode or transistor type.

It is known that, in double triode synchronous detection circuits, the detected signal is extremely sensitive to the amplitude variations of the locally supplied square wave signal which is combined with the incoming signal to be detected. By double triode circuit is here meant a circuit comprising two vacuum tube or semiconductor devices, having each at least three electrodes.

It is an object of the invention to avoid this drawback. To this end the invention provides an improved synchronous detection circuit, whose output is much less liable to vary with the amplitude variations of the local signal.

The synchronous detection circuit according to the invention essentially comprises two double triode circuits associated to provide an output signal practically independent of the local signal amplitude.

The invention will be best understood from the following description with reference to the appended drawing in which:

FIG. 1 shows a conventional double triode type synchronous detector;

FIG. 2 shows the various signals which are combined in the circuit of FIG. 1;

FIG. 3 discloses a simplified diagram which affords a better understanding of the circuit of FIG. 1; and

FIG. 4 shows a synchronous detection circuit according to the invention.

It is recalled that the synchronous detection consists essentially in mixing the incoming periodical signal to be detected with a locally supplied periodical signal of the same frequency and constant amplitude. More specifically, in the case of a double triode synchronous detector, the incoming wave $S(\omega t)$ and its opposite $-S(\omega t)$ are combined with a square wave $M(t)$, of the same period $T=2\pi/\omega$, and its opposite $-M(t)$.

Signals $-S$ and $-M$ are readily obtained. For example, the incoming signal and its opposite can be supplied by an amplifier, with symmetrical outputs and signals M and $-M$ by a local oscillator with symmetrical outputs.

Referring to FIG. 1, there is shown a double triode T_0 , whose plates are directly coupled to the positive terminal of a D.-C. power supply, and whose cathode is coupled through a resistor R_4 to the negative terminal of the same source. Grids g_1 and g_2 are respectively grounded through equal resistors R_{31} and R_{32} . Grid g_1 receives signal S through a coupling capacitor C_{11} and a resistor R_{11} and signal M through a coupling capacitor C_{21} and a resistor R_{21} . Grid g_2 receives signal $-S$ through a capacitor C_{12} and a resistor R_{12} and signal $-M$ through a capacitor C_{22} and a resistor R_{22} . Components R_{12} , R_{22} , R_{32} , C_{12} and C_{22} , on the one hand, and the components R_{11} , R_{21} , R_{31} , C_{11} and C_{21} on the other hand, are respectively identical. Components R and C build up a filter at the output of which signal V_d is collected. The potentials of the grids g_1 and g_2 are respectively

$$V_{g1} = \lambda M(t) + \mu S(t)$$

$$V_{g2} = -\lambda M(t) - \mu S(t)$$

2

wherein

$$\lambda = \frac{R_{11} \cdot R_{31}}{R_{21}(R_{11} + R_{31}) + R_{11} \cdot R_{31}} = \frac{R_{12} \cdot R_{32}}{R_{22}(R_{12} + R_{32}) + R_{12} \cdot R_{32}}$$

and

$$\mu = \frac{R_{22} \cdot R_{32}}{R_{12}(R_{22} + R_{32}) + R_{22} \cdot R_{32}} = \frac{R_{12} \cdot R_{31}}{R_{11}(R_{21} + R_{31}) + R_{21} \cdot R_{31}}$$

The common cathode potential V_d , which is the filtered output signal of the detector, follows, to within a fixed bias voltage, the higher grid potential.

Referring to FIG. 2, curves a , b , c , and d show respectively signals S , $-S$, M and $-M$, curves e and f voltages V_{g1} and V_{g2} , and curve g voltage V_d as a function of time.

Voltage V_d is the sum of a D.-C. component λM_0 , M_0 being the amplitude of the square wave $M(t)$, and of an A.-C. signal $V(t)$ which can be diagrammatically derived from signal $S(\omega t)$ by means of the arrangement of FIG. 3 which is essentially a reversing switch with four terminals 1 , 2 and $1'$, $2'$, operating at the fundamental frequency of $S(\omega t)$; i.e. being in position 1 , $1'$, during the first half period and in position 2 , $2'$ during the following half period. It can thus be said that $V(t)$ results from the multiplication of $\mu S(\omega t)$ and the transfer function τ of the reversing switch. This function is a square wave signal of period T , varying between $+1$ and -1 .

Then,

$$30 \quad \tau = \frac{4}{\pi} \left[\cos \omega t + \frac{1}{3} \cos 3\omega t + \dots + \frac{1}{2n+1} \cos (2n+1)\omega t + \dots \right] \quad V(t) = \mu \tau S(\omega t)$$

and

$$35 \quad V_d = \lambda M_0 + \mu \tau S(\omega t)$$

$S(\omega t)$ being of the form:

$$S(\omega t) = S_1 \sin (\omega_0 t + \varphi_1) + S_2 \sin (2\omega_0 t + \varphi_2) + S_3 \sin (3\omega_0 t + \varphi_3) + \dots$$

40 one can write:

$$V_d = \lambda M_0 + \mu [S_1 \sin (\omega_0 t + \varphi_1) + S_2 \sin (2\omega_0 t + \varphi_2) +$$

$$45 \quad S_3 \sin (3\omega_0 t + \varphi_3) + \dots] \left[\frac{4}{\pi} \left(\cos \omega t + \frac{1}{3} \cos 3\omega t + \frac{1}{5} \cos 5\omega t \right) + \dots \right]$$

The D.-C. component of the signal, at the output of filter RC coupled to the cathodes is:

$$50 \quad \bar{V}_d = \lambda M_0 + \frac{\mu}{2\pi} \int_0^{2\pi} \tau S(\omega t) d(\omega t)$$

or

$$55 \quad \bar{V}_d = \lambda M_0 + \frac{2\mu}{\pi} \left(S_1 \cos \varphi_1 + \frac{S_3}{3} \cos \varphi_3 + \frac{S_5}{5} \cos \varphi_5 + \dots \right)$$

It can be seen that the harmonics of the order $2n$ are cancelled, while the amplitudes of the harmonic of the order $(2n+1)$ divided by $(2n+1)$.

If now a low-pass filter is inserted, say in the amplifier circuit providing signal $S(\omega t)$, which filter eliminates the harmonics starting from the third harmonic, the filter RC being such that $RC > 1/\omega_0$, one obtains at the output of this latter filter a D.-C. voltage

$$65 \quad \bar{V}_d = \lambda M_0 + \frac{2\mu}{\pi} S_1 \cos \varphi_1$$

This arrangement thus makes it possible to separate a fundamental component from the noise components. However, the arrangement has a substantial drawback. M_0 being generally great compared to $S(\omega t)$ to insure

the linearity of the detector over a wide range, signal $\bar{V}_d$ so obtained will be very sensitive to variations of M_0 . For example, with $M_0=20$ volts for

$$\frac{2\mu}{\pi} S_1 \cos \varphi_1 = 2 \text{ volts}$$

5

a 5% variation of M_0 , i.e. a variation by one volt, results in a variation by 1 volt of the amplitude of the detected signal, that is to say a variation equivalent to that produced by a 50% increase of the incoming signal to be detected. In other words the effect due to any drift of signal M_0 may be very significant.

FIG. 4 shows a synchronous detector according to the invention.

The circuit comprises two identical double triodes T_0 and T'_0 , similar to the triode of FIG. 1.

Grids g'_1 and g'_2 receive in the same manner signals $+S$ and $-M$, on the one hand and, $-S$ and $+M$, on the other.

The same reference numbers are used for the same components related to tube T_0 in FIG. 1 and FIG. 4. Those associated with tube T'_0 carry the same reference numbers with a dash. The output filter which is the same as in FIG. 1 has not been shown in FIG. 4. It is inserted between resistors R_4 and R'_4 . The plates of triodes T_0 and T'_0 are connected to the positive terminal of the supply source and both cathodes are connected to the negative terminal through resistors R_4 and R'_4 respectively.

According to the relations established above, the output voltage $\bar{V}_d$ can be written:

$$\bar{V}_d = \lambda M_0 + \frac{2\mu}{\pi} S_1 \cos \varphi_1 - \left(\lambda' M_0 - \frac{2\mu'}{\pi} S_1 \cos \varphi_1 \right)$$

with

$$\lambda' = (R'_{11} \cdot R'_{31}) / (R'_{11} + R'_{31}) + R'_{11} \cdot R'_{31}$$

and

$$\mu' = (R'_{22} \cdot R'_{32}) / (R'_{12} + R'_{32}) + R'_{22} \cdot R'_{32}$$

If triodes T_0 and T'_0 and the related circuits are perfectly identical, $\lambda' = \lambda$ and $\mu' = \mu$, yielding

$$\bar{V}_d = \frac{4\mu}{\pi} S_1 \cos \varphi_1$$

In other words the output signal is independent of M_0 . If there is a difference between λ' and λ on the one hand and μ and μ' on the other, one has

$$\bar{V}_d = \frac{2}{\pi} (\mu + \mu') S_1 \cos \varphi_1 + M_0 (\lambda - \lambda')$$

writing

$$\epsilon = \frac{\lambda - \lambda'}{\lambda}$$

it can be written

$$\bar{V}_d = \frac{2}{\pi} (\mu + \mu') S_1 \cos \varphi_1 + \epsilon \lambda M_0$$

The variation of $\bar{V}_d$ as a function of M_0 , i.e. $d\bar{V}_d/dM_0$, is divided by $1/\epsilon$ which is quite appreciable. With $\lambda M_0 = 20$ volts,

$$\frac{2\mu}{\pi} S_1 \cos \varphi_1 = 2 \text{ volts}$$

and assuming $\epsilon = 0.05$, which is the usual order of magnitude,

$$\bar{V}_d = 5 \text{ volts}$$

If then λM_0 drifts from 20 volts to 21 volts, i.e. undergoes a 5% variation, $\bar{V}_d$ varies only by 0.05 volt or only 1%.

The invention is obviously not limited to the particular embodiment shown; thus transistor or other tubes may of course be used instead of triodes.

What is claimed is:

1. A synchronous detector circuit for detecting a periodical signal comprising a first double triode having a first and a third grid and a first cathode output; a second double triode having a second and a fourth grid and a second cathode output; means for coupling said triodes in parallel to a high voltage source; means for applying said signal respectively to said first and second grids; means for applying to said third and fourth grids the same signal with a reversed phase; means for applying a square wave with the same period as said signal to said first and fourth grids; means for applying said square wave with a reversed phase to said third and second grids; and means for collecting an output voltage between said first and second cathode outputs.
2. A synchronous detector circuit for detecting a periodical signal comprising: a first double triode having a first and a third grid and a first cathode output; a second double triode having a second and a fourth grid and a second cathode output; means for coupling said triodes in parallel to a high voltage source; identical circuit means for applying said signal respectively to said first and second grids; and for applying to said third and fourth grids the same signal with a reversed phase; identical circuit means for applying a square wave with the same period as said signal to said first and fourth grids and for applying said square wave with a reversed phase to said third and second grids; and means for collecting an output voltage between said first and second cathode outputs.
